UNITED STATES PATENT OFFICE.

FREDERICK W. TATTERSALL, OF PHILADELPHIA, PENNSYLVANIA.

ENGINE-REGISTER.

SPECIFICATION forming part of Letters Patent No. 297,872, dated April 29, 1884.

Application filed April 21, 1881. (No model.)

To all whom it may concern:

Be it known that I, FREDERICK W. TATTERSALL, of the city of Philadelphia, in the county of Philadelphia and State of Pennsylvania, have invented certain new and useful Improvements in Counters for Engine-Registers; and I do hereby declare that the following is a full, clear, and exact description of the invention, which will enable others skilled in the art to which it appertains to make and use the same, reference being had to the accompanying drawings, and to letters of reference marked thereon, which form a part of this specification.

15 Figure 1 is a top view of my improved register. Fig. 2 is a side elevation of the same. Fig. 3 is a diagram showing the peculiar interlocking of the dial-wheels when fixed and when changing, and the location of the driving-tooth 20 in the middle of the opening of the upper rim of the wheel.

The same letter indicates the same part wherever it occurs in the drawings.

The object of my invention is to simplify the 25 construction of an engine-register invented by Cyrus Chambers, Jr., for which an application for a patent is filed simultaneously with my present application.

My improvements on that machine consist 30 in dispensing with the independent spur-gears and driving-teeth, changing the manner of interlocking the flanged rims of the dial-wheels, locating the driving-spurs inside the periphery of the upper rims of the dial-wheels, and 35 fixing those wheels on vertical shafts, thus occupying much less room and greatly economizing the cost of manufacture, all as hereinafter more specifically set forth.

In carrying my improvements into practice 40 I place on a series of parallel upright shafts a series of dial-wheels like those used in Chambers's machine, diagonally arranged relatively to the frame, and provided with flanged rims projecting both up and down from the body of 45 the wheel, like the flange of a pulley. Each rim has in its lower edge ten equidistant notches or openings, and in its upper edge a larger opening divided by an interposed driving-tooth. The upper edge of the flanged rim 50 of each wheel engages with two of the notches of the under edge of the wheel next on its left, so as

to interlock with said wheel at all times and prevent it from moving until the opening *o* in front of the driving-tooth is brought by revolution into position to allow the notches of the driven wheel to pass within the upper rim of the driving-wheel at the moment the driving-tooth engages a notch on the lower rim of the driven wheel, and revolves it a distance equal to one-tenth of a revolution. The digits from 1 to 0 55 are marked on the faces of the flanges, and indicate through openings in a perforated dial (not shown) the movement of the wheels in a decimal series in the well-known way, each wheel, by an entire revolution, moving the 60 wheel on its left one-tenth of a revolution, all in the manner hereinafter more specifically set forth.

In the drawings, A marks the frame of the machine; B C D E F, a series of parallel vertical shafts turning in the frame, and carrying a series of dial-wheels, G H I J K, provided with flanged rims having in their upper edges, *f*, an opening, *m m*, divided by a tooth, *t*, and in their lower edges ten equidistant notches, *n* 65 *n*, as most clearly seen in Fig. 3.

Of the flanged disk-wheels, G is the driving-wheel; H, the "units-wheel;" I, the wheel for "tens;" J, that for "hundreds;" and K for "thousands." The ten digits from 1 to 0 are 70 marked upon the faces of the several wheels above the notches, as shown. They are read, in the usual way, through a perforated face or dial. (Not shown.)

The operation is as follows: Shaft B receives 75 rotation by means of any suitable or convenient connection from the engine whose revolutions or strokes it is designed to count and register. For every revolution of the engine the disk G makes one revolution. Its upper 80 flanged rim, *f*, is locked in two of the lower notches of the units-wheel H (in the manner shown by the broken wheel on the right hand of Fig. 3) until the opening *m*, passing under its rim, allows wheel H to turn one-tenth of a 85 revolution under the impulse of tooth *t* on wheel G. Each revolution of wheel G causes the wheel H to move one notch. Ten revolutions of wheel G produce one revolution of wheel H. The same ratio of movement and 90 the same mode of operation prevail throughout the entire series of wheels, to whatever

number it may be extended. Every movement is positive, the flanged rims are always interlocked, and every wheel is immovable until the movement becomes necessary to indicate a change of count. The direction of movement of each wheel is indicated by the arrow upon it, and the order of the digits upon each is arranged accordingly, so as to give the proper reading at the dial at each revolution 10 of the engine.

I disclaim any and all of the devices or mechanisms shown in Patent No. 215,104, Reissue No. 9,118, and English Patent No. 1,957 of 1862.

15 My hereinbefore-described invention is an improvement upon a certain engine register or counter invented by Cyrus Chambers, Jr., who filed an application for Letters Patent for his invention on or about the 13th day of April, 20 1881.

The improvement consists, simply, in removing a portion of the flange or rim of the interlocking-wheels of the said device of Cyrus Chambers, Jr., and inserting the propelling-tooth *t* upon the wheels in the interval between the ends of the flanged part, whereby the tooth of one wheel serves to propel the adjacent wheel by impinging against the projections successively on the lower rim of the 30 latter, as described and hereinafter claimed.

In said device of Cyrus Chambers, Jr., the registering-wheels are driven by means of the combination of a toothed wheel fixed to the shaft of the registering-wheel with a tooth or spur which projects from the shaft of the preceding 35 wheel, so as to engage with the teeth of the said toothed wheel successively.

Having thus described my invention, I wish it to be understood that I do not claim anything described and shown in English Patent No. 40 1,957 of 1862, United States Patents Nos. 215,104, 221,652, and Reissue No. 9,118; but

What I claim, and desire to secure by Letters Patent, is—

In an engine-counter, a train of register or 45 dial wheels, each provided with a double-flanged rim, one edge of which rim having a driving-tooth in a slot or interval therein, and the other or opposite edge having a series of notches therein, said train of wheels being constructed, 50 combined, and arranged in successive relation to each other in the manner shown, and for the purposes described.

In testimony that I claim the foregoing as my own I affix my signature in presence of two 55 witnesses.

F. W. TATTERSALL.

Witnesses:

PATRICK DONLEY,
I. H. CHAMBERS.
